Des. 228,963
Patented Oct. 30, 1973

228,963

CRANKCASE EMISSION FLUID SEPARATOR

Vernon L. Mihm, 4736 Isabella Ave., Fair Oaks, Calif. 95628; and William E. White, 4430 Barrett Road; and Stanley Watson, 6448 Rampart Drive, both of Carmichael, Calif. 95608

Filed Apr. 16, 1971, Ser. No. 134,931

Term of patent 14 years

Int. Cl. D15—01

U.S. Cl. D77—1 A

Fig. 1

Fig. 2

Fig. 3

Fig. 4

Fig. 5

FIG. 1 is a side elevational view of a crankcase emission fluid separator showing our new design, the opposite side being substantially similar in appearance;

FIG. 2 is a front elevational view;

FIG. 3 is a bottom plan view;

FIG. 4 is a top plan view; and,

FIG. 5 is a rear elevational view.

We claim:

The ornamental design for a crankcase emission fluid separator, as shown and described.
